(57) **CLAIM**

The ornamental design for a hood for an automobile, as shown and described.

DESCRIPTION

FIG. 1 is a front elevational view of a hood for an automobile in accordance with our new design;

FIG. 2 is a top plan view of the hood in accordance with our new design of FIG. 1;

FIG. 3 is a left side elevational view of the hood in accordance with our new design of FIGS. 1 and 2;

FIG. 4 is a right side elevational view of the hood in accordance with our new design of FIGS. 1 to 3;

FIG. 5 is a front side perspective view of the hood in accordance with our new design of FIGS. 1 to 4;

FIG. 6 is a cross sectional view of the hood in accordance with our new design as seen along a section line 6-6 of FIG. 4;

FIG. 7 is a cross sectional view of the hood in accordance with our new design as seen along a section line 7-7 of FIG. 4; and,

FIG. 8 is a cross sectional view of the hood in accordance with our new design as seen along a section line 8-8 of FIG. 4.

The rear view and bottom view of the hood form no part of the claimed design.

The appearance of the bottom of the hood as seen in FIGS. 3 and 4 is for purpose of illustrating the boundaries of the exterior surface of the hood, and forms no part of the claimed design.

The cross sectional views of FIGS. 6-8 are provided to clarify the exact contour or configuration of the exterior surface of the hood, and no attempt is made to illustrate features of internal construction.
